PLACE MAT OR SIMILAR ARTICLE

William M. Feder, New York, N. Y., assignor to Hedwin Corporation, a corporation of Maryland

Application April 28, 1951, Serial No. 15,008

Term of patent 14 years

(Cl. D92—26)

To all whom it may concern:

Be it known that I, William M. Feder, a citizen of the United States, residing at New York city, in the county of New York and State of New York, have invented a new, original, and ornamental Design for Place Mat or Similar Article, of which the following is a specification, reference being had to the accompanying drawing, forming part thereof.

In the drawing

Fig. 1 is a top plan view of a place mat or similar article showing my new design;

The place mat is shown against a black background to better bring out the details of the design.

I claim:

The ornamental design for a place mat or similar article, as shown and described.

WILLIAM M. FEDER.
